US0D1040514S

(12) **United States Design Patent** (10) **Patent No.:** **US D1,040,514 S**
(45) **Date of Patent:** **** Sep. 3, 2024**

(54) **STORAGE CASE**

(71) Applicant: **HTC Corporation**, Taoyuan (TW)

CN 305996279 8/2020
CN 306517086 5/2021

(72) Inventors: **Wei-Ting Hsiao**, Taoyuan (TW);
Yien-Chun Kuo, Taoyuan (TW)

(Continued)

(73) Assignee: **HTC Corporation**, Taoyuan (TW)

(**) Term: **15 Years**

(21) Appl. No.: **29/897,080**

(22) Filed: **Jul. 11, 2023**

Related U.S. Application Data

(62) Division of application No. 29/813,743, filed on Nov. 1, 2021, now Pat. No. Des. 1,027,444.

(51) **LOC (14) Cl.** **03-01**

(57) **CLAIM**

The ornamental design for a storage case, as shown and described.

DESCRIPTION

FIG. 1 is a perspective view of a storage case showing the new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines immediately adjacent the claimed areas represent the bounds of the claimed design while all other broken lines are directed to environment and are for illustrative purposes only. The broken lines form no part of the claimed design.

1 Claim, 7 Drawing Sheets
